COCKING DEVICE FOR AUTOMATIC FIRE-
ARMS HAVING A SLIDING BARREL AND
A BOLTED BREECH

Karl Kehne, Dusseldorf-Oberkassel, Germany,
assigner to Waffenfabrik Solothurn A. G., Solo-
thurn, Switzerland, a corporation of Switzer-
land

Application November 6, 1933, Serial No. 696,894
In Germany March 11, 1933

2 Claims. (Cl. 42—4)

In the case of automatic firearms having a sliding barrel and a bolted breech, of large calibre for instance of the order of magnitude of 2 cm. calibre and upwards, the opening of the breech for the purpose of loading the weapon occasionally involves considerable difficulty because at least in the first part of the opening movement up to the unbolting of the breech, the resistance of the means of retraction, i. e. the closing spring for the breech and also the retraction device for the barrel, which are generally arranged separately, must be overcome. These opposing forces are so great that it is only by very great exertion on the part of the gunner 10 that they can be overcome by means of the rectilinearly moved handle on the breech such as is usually provided in the case of machine guns of small calibre.

In order to facilitate the loading of large-bore guns of this kind, the invention provides a cocking device which, for the common return travel of the barrel and breech up to the point at which unbolting occurs, brings into action between these parts and the hand of the gunner a transmission device which assists the hand pull.

With this object in view, in a particularly advantageous form of construction, the handle for drawing back the barrel and breech members is designed in the form of a lever which is pivotally mounted on a longitudinally sliding member in the frame of the gun, which lever by a shorter arm of the breech block bolted to the barrel in the forward position, imparts backward movement of at least the length of the course necessary for the unbolting of the breech, and then, while continuing the movement in a straight line, moves the unbolted breech alone further back.

With this arrangement, for the entire process of opening the breech, only a moderate pull need be applied to the handle, said pull, during the temporary opposing action of the two means of retraction, being strengthened to a sufficient extent as a result of the mechanical advantage of the lever system.

A typical embodiment of the subject of the invention is shown in the drawing.

Figure 1 is a longitudinal section through the middle part of the firearm.

Fig. 2 is a plan view on a middle section of a firearm showing the cocking device according to the invention, the cocking lever being pulled back from the position shown in dot and dash lines, and

Fig. 3 is a cross-section taken on line III—III 55 of Fig. 2.

The frame *a* of the weapon is closed at the top in known manner by a cover member *a*₁ accommodating the breech retractor spring *a*₀ and also accommodating the barrel *b*₁ together with the breech casing *b* seated thereon, so as to be capable of longitudinal displacement against the action of the running out spring *b*₀. The breech *c* which slides in the casing *b* is provided with an arm *c*₁ which protrudes laterally through a longitudinal slot in the housing, with which, for the loading of the weapon, the cocking lever *d* engages. This lever *d* is pivotally mounted about the pin *d*₁ in the sliding member *e* which slides in the longitudinal guideway *a*₂, and rests with a pin *d*₃, arranged at its lower side, in the vicinity of its pivotal axis, in front of the arm *c*₁ of the breech.

A spring plunger *f* mounted in the cover member *a*₁ of the weapon, by its engagement with the projection *d*₄ on the free end of the cocking lever carrying at the top the handle *d*₀, on one hand secures the cocking lever folded down against the frame of the gun against involuntary swinging out from its position of rest and on the other hand also prevents the cocking lever support *e* resting at the front against the edge *a*₀ of the frame from moving backwards.

In order to cock and load the gun, the handle *d*₀ is first of all drawn out sideways from the dot and dash line position to the full line position until the spring plunger *f* comes out of engagement, and the handle is then drawn backwards. In this operation it swings about its pivot *d*₁, and after a certain idle movement, by contact of its pin *d*₃ with the arm *c*₁ takes the breech, together with the breech casing *b* bolted thereto, and the barrel *b*₁, against the action of the barrel and breech retraction springs *b*₀ and *a*₀, with a force which is increased in proportion to the length of the lever arms *d*₀—*d*₁ to *d*₁—*d*₃; backwards until the breech is unbolted from the breech casing and the barrel, and is disconnected from these parts.

On a further pull being applied to the lever *d*₀ which is now directed backwards, its hitherto swinging movement becomes a straight-line movement, in which its support *e* joins, and which returns the breech, under the tension merely of its own closing spring, into the rear end position.

If the tension lever *d* is now released it swings forward under the action of a spring *d*₂ mounted in its pivot *d*₁ up to the frame of the weapon, and then, together with its sliding member *e*, is carried along by the forwardly moving breech into its position of rest, in which it remains secured

by the plunger *f*, even during the subsequent movements of the barrel and breech during firing.

I claim:—

1. An automatic firearm having a short recoil 5 barrel and a longitudinally movable breech latching to the barrel, comprising separate run out means for the barrel and breech, means for cocking the firearm manually consisting of a cocking lever rotatably mounted on the firearm for the 10 common retraction of the barrel and breech and longitudinally slidable for further withdrawing the unlatched breech alone into the cocked position, and a spring pressed plunger provided on the barrel which engages with the front end of 15 the cocking lever to prevent involuntary swinging of the lever in its position of non-use.

2. An automatic firearm comprising a frame, a breech block having an arm, a slideable member, a rotatably mounted locking lever pivotally mounted on the slide member longitudinally guided in the frame of the gun and engaging with the breech, a handle on the outer end of the cocking lever and a pin near its pivotal end, said pin in rotating the lever abutting against said arm of the breech block exerting a thrust for common return travel of the locked breech and barrel up 10 to at least their point of unlocking position, and then continuing the cocking movement in a straight line for moving the unbolted breech alone further back. 5
